UNITED STATES PATENT OFFICE.

ROBERT DOUGLAS, OF RAVENA, NEW YORK.

VINEGAR-GENERATOR.

SPECIFICATION forming part of Letters Patent No. 726,883, dated May 5, 1903.

Application filed May 20, 1902. Serial No. 108,182. (No model.)

To all whom it may concern:

Be it known that I, ROBERT DOUGLAS, a citizen of the United States, residing at Ravana, Albany county, New York, have invented 5 certain new and useful Improvements in Vinegar-Generators; and I do hereby declare the following to be a full, clear, and exact description of the invention, such as will enable others skilled in the art to which it appertains 10 to make and use the same, reference being had to the accompanying drawings, and to the figures of reference marked thereon, which form a part of this specification.

The object of my invention is to provide a 15 new and improved vinegar-generator which may also be used for a generator for other acids and liquids.

In the drawings, Figure 1 shows a side elevation of one form of my generator with a portion 20 of its side broken away, showing the fiber bundles and their arrangement; Fig. 2, a plan view of the perforated top, partly broken away to show the ends of the bundles; Fig. 3, a plan of the grating preferably used in my 25 generator; Fig. 4, a side elevation of one of the fiber bundles; Fig. 5, an edge view of one of the sustaining-posts, showing pins passing through it; Fig. 6, a similar view of one of the posts, showing the preferable way of attaching the binder; Fig. 7, a side elevation 30 of one of the fiber bundles in operative construction, and Fig. 8 a similar view of another fiber bundle differently arranged and assembled.

35 In vinegar-generators and similar devices in common use the generator, cistern, or tun is more or less filled with a loose-lying substance through which the wash may easily pass and slowly percolate—such as shavings, 40 corncobs, and various other materials—laid and assembled so that as the wash percolates downward from the top air is allowed to ascend through the said material, and thus aerate, oxidize, and otherwise act upon the 45 wash as it descends in thin streams and drops. Also fibrous material has been braided in long braids and been suspended from their upper ends and been allowed to hang freely, down which the wash has been allowed to run. The 50 difficulty with all such arrangements has so far been that shavings, corncobs, braids, and other free-to-move material used swells and

packs firmly together, and the braids also swell and form an almost impervious body, so that the wash will run down their outer 55 surfaces only, and the air cannot pass upward through the fibers, shavings, or cobs, but only through such openings as may by chance exist between the masses, precisely as it would find its way through the interstices formed in 60 a generator packed with cobble or other reasonably small stones, the stones being compact masses through which no air could pass, with this difference, however, that the interstices between the cobs, shavings, and braids 65 would grow less and less as the material became soaked and swelled, until in a short time the whole mass was so tightly compressed by this swelling that operation was practically impossible, and the generator had to be 70 refilled and repacked at considerable expense and loss of time. With a generator arranged as my generator is shown to be I avoid all these difficulties and am able to produce a far greater product in a given time than has 75 heretofore been done by any generator known to me.

A full description of my generator is as follows:

The numeral 1 shows the cistern or tun, 80 made of wood, preferably.

2 shows the foraminous head, allowing of the wash as it is poured over the same passing into the cistern in streams well distributed over the ends of the end surfaces of the 85 fiber bundles 4, where it begins its passage through the interstices between each of the fibers of which it is composed.

3 is a grating which I use in large generators, (in smaller ones it may be omitted, if desired,) set about the middle of the cistern, separating the two sets of fiber bundles, as seen in Fig. 1. As the wash percolates through the above-mentioned interstices of the material of the fiber bundles 4 it meets the rising 90 currents of air entering the openings 5 and passing through the lower chamber and up through the bundles and is aerated, oxidized, and otherwise acted upon by the air. These fiber bundles and their arrangement and assembling are the essential part of my invention, and I proceed to fully describe them. Each of the bundles consists of some fibrous or string-like material—such as shredded

ratan, excelsior, or other material suitable for the purpose—that can be formed into string-like condition, and such fibers or strings are loosely wound, preferably, about posts or supports 4' and tied loosely thereto by cords or fibers 8. To the better prevent the fibers or strings from becoming packed together and swelling, so as to close the interstices between each fiber or string composing each bundle, pins or projections are arranged in connection with the posts 4', as seen at 4", the ends of which pass into the bundles and between the fibers and support them so that the fibers cannot mat together, so that in actual use each fiber or string will stand separate from the other as much as possible and not lay close together in a compact mass, as they would if formed in braids or packed together, and thus permit the air to pass upward through the interstices and the vinegar downward through them. In the top of the posts, preferably, are holes through which the binding-cords are passed, as seen, and when this string or binder is wrapped about the fiber, loosely bringing the fibers together about the posts, it also prevents the mass of fibers forming the bundles from sagging and compacting, and as the fibers are loosely held in the bundle the material of them may swell without closing the interstices. It will also be noticed that the ends of the bundles are not cut off so as to make a blunt end, but are left more in the nature of tufts, so as to present as many ends for the wash to follow as possible.

In Fig. 4 I show one of the fiber bundles as it is first formed and afterward, as seen in Figs. 4 and 5, two or more of them bound loosely to the posts 4', as above described. This is the preferable way of forming and binding them; but it is evident that other methods may be used without departing from the spirit of my invention.

Another advantage of my invention is: The cisterns or tuns being very heavy often settle and stand out of plumb or truth, in which

cases when packed as is commonly done or when braids are hung from their upper ends and allowed to have free movement at their lower ends the material will settle to one side, leaving the upper side fallen away from the side of the cistern, thus leaving a large open space, down which the vinegar or wash passes without being broken up into thin streams and drops, and proper aeration is not had.

It will be seen by viewing Fig. 1 that the bundles of fiber do not reach to the bottom of the cistern, but are sustained above the bottom to a height sufficient to form a suitable chamber, into which the wash may settle and be withdrawn by the cock 6, and openings 5, located above the surface of the confined wash, allow of the outer atmosphere entering above the liquid and passing upward through the bundles of fibers 4 and out at the perforations in the cover 2. When the grate 3 is used, the ends of the upper bundles are also sustained slightly above the grating, so that their lower ends shall not be matted by resting on it. The wash is fed to the perforated top 2 in any suitable manner and from thence passes into the cistern or tun.

Having now described my invention, what I claim is—

In a vinegar-generator a receiving tub or tank; bundles of fibrous material having interstices between the fibers, said bundles being supported in a practically upright position; immovable and non-compressible supports arranged to support the fibrous material of the bundles at intervals, means for introducing the wash and withdrawing it and means for creating a constant circulation of air through the interstices of the fibrous material substantially as described.

In testimony whereof I affix my signature in presence of two witnesses.

ROBERT DOUGLAS.
